UNITED STATES PATENT OFFICE.

EDWARD W. FIX, OF DANVILLE, ILLINOIS.

MAIL-BAG CATCHING AND DELIVERING MECHANISM.

No. 878,623.

Specification of Letters Patent.

Patented Feb. 11, 1908.

Application filed July 30, 1907. Serial No. 386,204.

To all whom it may concern:

Be it known that I, EDWARD W. FIX, a citizen of the United States, residing at Danville, in the county of Vermilion and State 5 of Illinois, have invented certain new and useful Improvements in Mail-Bag Catching and Delivering Mechanism, of which the following is a specification.

This invention relates to the subject of 10 mail pouch handling apparatus for railway cars, and has special reference to a simple and practical combination of devices constituting a catching and delivering mechanism comprising means for safely and accurately catching and delivering mail on and from a car in motion.

To this end the invention contemplates 15 a simple and practical construction of mail bag catching and delivering crane that can be manipulated with facility and despatch, while at the same time embodying means for positively catching and delivering a bag or pouch with perfect safety to the latter with the train moving at any rate of speed.

20 A further object of the invention is to provide a crane comprising a minimum number of parts, and capable of being readily attached to, and detached from, the door frame of the car, and also capable of being 25 readily swung into and out of the door opening in the operation of catching and delivering the bags.

Another object of the invention is to provide 30 a crane of an exceedingly light and durable construction which at the same time is capable of supporting and delivering any weight of mail that can be handled, and also adapted for supporting and delivering a single mail bag or pouch, or the maximum number 35 of bags or pouches which are delivered at any one station. Furthermore, the invention provides a construction which insures the delivery of the mail bags a sufficient distance out from the car so that the 40 same will not be drawn by the suction beneath the car wheels.

A further object of the invention is to associate 45 with the crane a simple and thoroughly practical catching device or fork capable of accurately and securely catching a bag suspended at the station, and thereby receiving the same on the mail car, and further in connection with the catching and delivering crane, the invention embodies a 50 novel construction of station bag receiver

which effectually receives the bag delivered from the car without injury thereto.

With these and many other objects in view, which will more readily appear as the nature of the invention is better understood, the same consists in the novel construction, combination, and arrangement of parts hereinafter more fully described, illustrated and claimed.

The essential features of the invention involved in carrying out the objects above indicated, are necessarily susceptible to a wide range of structural modification without departing from the scope of the invention, but a preferred embodiment of the latter is shown 65 in the accompanying drawings, in which:

Figure 1 is a perspective view of a complete mail bag catching and delivering mechanism for cars constructed in accordance with the present invention. Fig. 2 is a plan view 75 of the same. Fig. 3 is a sectional view on the line 3—3 of Fig. 2. Fig. 4 is a similar view on the line 4—4 of Fig. 2. Fig. 5 is a top plan view of the swinging end portion of the crane showing the same fitted with the supplemental bag carrier for increasing the carrying capacity of the crane. Fig. 6 is a front view of the construction shown in Fig. 5.

Like references designate corresponding 85 parts in the several figures of the drawings.

In carrying out the present invention, no change whatever is required in the ordinary equipment of a mail car, and the improved crane comprises, in its general organization, 90 the swinging crane proper designated in its entirety by the numeral 1, and a stationary supporting bracket 2, the latter being adapted to be screwed or otherwise fastened to one of the side jambs of the door frame of a mail car at a proper elevation for the convenient handling of the crane proper. Preferably, each jamb of all of the door frames of the mail car is fitted with the stationary supporting brackets 2, and a single crane 1 employed in 100 connection with all of said brackets, so as to meet every requirement of the mail service in delivering the mail from either side of the car, or with the car going in either direction. To provide for this, the crane proper 1 is not 105 only pivotally connected with its supporting bracket, but is also detachable therefrom, such connection being conveniently provided for by forming each bracket 2 at its upper and lower ends, with horizontally disposed 110

flanges 3 and 4 respectively, carrying the up-standing pivot studs 5 and 6 upon which the inner extremities of the crane frame are pivotally and detachably hooked.

5 The frame of the swinging crane essentially comprises a main lower frame bar 7 detachably and pivotally engaging at one end the pivot stud 6, the inclined brace arm 8 secured at its lower end, as at 9, to the bar 7, 10 and having its upper end detachably and pivotally engaged with the upper stud 5, and the rear vertical brace 7a.

The outer swinging end portion of the main frame bar 7 of the frame carries a reusable supporting latch device for the mail bag or bags. This device includes a supporting bolt 10, slidably working through the guide openings 11 of a U-shaped or equivalent keeper 12 and pivotally connected at 20 one end to a pivotal release trigger 13. The trigger 13 is pivoted intermediate its ends, as at 14, on the frame bar 7, and the keeper 12 is riveted or otherwise fastened to said frame bar. The hanger ring 15 at one end 25 of a mail bag or pouch is adapted to be hung on the bolt 10 within its keeper, and when the crane is swung outwardly to the position shown in Fig. 1, the outer end of the trigger 13 is adapted to come in contact with a post 30 or equivalent abutment 16 along side of the track. When this occurs, the trigger is rocked on its axis, and withdraws the bolt 10 from its keeper and from the hanger 15 of the mail bag, thereby releasing and delivering 35 the latter.

In practice, several mail bags are fastened together by engaging a snap on one with an extra hanger ring 15a on another, so that as many as three bags could be hung on, and 40 delivered from, a single supporting bolt 10, and to still further increase the capacity of the crane, there may be employed a supplemental bag carrier 17.

The supplemental carrier 17 may conveniently consist of a cross bar having a central keeper hole 18 engaging over a supporting pin 19 on the crane proper, and also provided with brace arms 20 engaging upon opposite sides of the frame bar 7 and beneath 50 the flanged stop bar 21 fastened on said frame bar 7 and acting as a stop for the trigger 13 when thrown in either direction. The supplemental carrier bar 17 is equipped at both ends with a supporting latch device 55 having the same construction and action as the one already described; hence the same references will apply to similar parts of the several latch devices. With the supplemental carrier, it will be observed that as 60 many as nine mail bags could be handled and delivered with facility.

In its operative position for catching and delivering a mail bag, the crane 1 is swung outwardly from the door to a position at substantially right angles to the body of the car

so as to overhang the road at the side of the track, and in this position the crane is preferably temporarily braced against movement in either direction so as to resist the shock of catching and delivering a bag, by 70 means of a brace rod 22 detachably hooked at one end, as at 23, in the lower frame bar 7 of the crane, and at its other end provided with an eye or loop 24 which may be conveniently hooked over one of the pivot studs 75 of the stationary bracket on the door jamb opposite the bracket carrying the crane, all of which is plainly shown in Fig. 1 of the drawings.

With the crane in the position referred to, 80 and the mail bag suspended from the supporting latch device therefor, the bag is adapted to be carried by the moving car directly into the flared mouth 25 at one end of a horizontally arranged receiving chute 26 85 arranged along side of the track and carried at the upper end of a station bag receiver designated in its entirety by the number 27. This bag receiver essentially comprises a stand 28, and an upright trapping box 29 90 built within the stand and open at top and bottom to provide for the reception and discharge of the mail bag or bags received from the passing car. The trapping box 24 is provided at the upper end with the 95 horizontally arranged bag receiving chute 26 100 open throughout and having projecting portions at both sides of the vertical plane of the box proper to provide the flared entrance mouth 25 previously referred to. By 105 reason of this construction, the station bag receiver will receive the mail bags from either end thereof, and at a point centrally between the opposite mouths 25, and, within the plane of the vertical center of the box 29, there is arranged the combined buffer and deflector 30 in the form of a valve or valve plate pivotally hung at its upper end, as at 110 31, between the sides of the chute 26, and disposed transversely of said chute so that an incoming bag from either direction will strike against the said deflector 30, causing the lower end of the latter to swing against one side of the box 29 (as shown in Fig. 1) and thereby deflect the bag downward 115 through the box 29 into the rope or equivalent catch net 32 detachably hung, as at 33, within the stand 28 beneath the lower discharging end of the box 29.

In carrying out the invention, certain 120 standards of the stand 28 may be utilized as the posts or abutments 16 engaged by the trigger 13 of the latch device, and also, these posts or abutments may be provided at their upper ends with hanger arms 34 carrying 125 pivotal tripping elements 35 from which the mail bag is suspended to be caught by the device on the car. A mail bag which is thus suspended at the station for delivery to the car is designed to be caught bodily by a 130

catching fork 36 carried by the swinging crane 1. This catching fork is arranged at right angles to the body of the car and essentially comprises a pair of curved, oppositely arranged grasping horns 37 pivotally mounted at their inner ends, as at 38, on one end portion of a carrying bar 39. This carrying bar is designed to be reversibly placed on the lower frame bar of the crane and is detachably fastened to said bar by any suitable means. One way of fastening the bar 39 in place is suggested in the drawings and consists in providing said bar 39 with a pair of spaced cleat pieces 40 engaging respectively upon opposite sides of the frame bar 7, and whose opposite ends are respectively engaged by a sliding keeper loop 41 on the bar 7, and beneath the flanged stop bar 21, as may be plainly seen from the several figures of the drawings. This detachable fastening permits a reversal of the catching fork according to the direction in which the crane is employed, and also permits the crane to be used with or without the fork.

25 The pivotal grasping horns 37 are provided with a toggle link connection 42, at the center of which is pivotally connected, as at 43, one end of a ratchet locking bar 44 loosely working through the keepers 45 carried by the bar 39 and engaging with a fixed holding tooth 46 also carried by the bar 39. With the horns 30 spread open as shown in Figs. 1 and 2, the impact of the mail bag against the toggle 42 will tightly close the 35 horns on the bag and the ratchet locking bar will slide back over the tooth 46, and, becoming engaged therewith when the horns are closed, will lock the latter closed so that there is no danger of dropping the bag till 40 pulled into the car.

Various changes in the form, proportion, and minor details of construction may be resorted to without departing from the spirit or sacrificing any of the advantages of the 45 invention.

I claim:

1. In an apparatus of the class described, a supporting bracket, a swinging crane hinged to said bracket, and a bag supporting 50 latch device mounted on the swinging end of the crane and consisting of a fixed keeper, a supporting bolt slidably working in said keeper, and a trigger pivotally mounted and

having a pivotal connection at one end with said bolt. 55

2. In an apparatus of the class described, the combination with a crane carrying a tripping bag supporting device, of a station bag receiver comprising an upright trapping box, a horizontal receiving chute at the top 60 of and in communication with said box, open entrance mouths at both ends of the chute, and a pivotally suspended combined buffer and deflector hung transversely of the chute within the top portion of the trapping 65 box.

3. In an apparatus of the class described, the combination with the crane carrying a tripping bag supporting device, of a station bag receiver comprising a trapping box having 70 a receiving chute at the top, a pivotal deflector mounted transversely within the receiving chute, and a rope net supported beneath said box.

4. In an apparatus of the class described, 75 the combination with a station bag hanger and a fixed abutment, of a crane carrying a tripping bag supporting latch device co-operating with said abutment, and a reversible self-clutching catching fork co-operating 80 with said bag hanger.

5. In an apparatus of the class described, the combination with a fixed abutment and a bag hanger at the station, of a crane carrying a tripping bag supporting device co-operating 85 with said abutment, and a catching device detachably and reversibly mounted on the crane, said catching device comprising a carrying bar, a pair of oppositely arranged grasping horns pivoted to said bar, 90 a toggle connection between the horns, and a self-acting locking device for said toggle connection.

6. In an apparatus of the class described, a crane carrying a single tripping bag receiving latch, and a supplemental carrying 95 bar detachably secured upon the swinging end of the crane and carrying a plurality of tripping bag supporting latches.

In testimony whereof I hereunto affix my 100 signature in the presence of two witnesses.

EDWARD W. FIX.
